CLAIM

The ornamental design for a controller for computer, as shown and described.

DESCRIPTION

FIG. 1 is a front side perspective view of a controller for computer showing our new design;

FIG. 2 is a back side perspective view thereof;

FIG. 3 is a front view thereof;

FIG. 4 is a back view thereof;

FIG. 5 is a top view thereof;

FIG. 6 is a bottom view thereof;

FIG. 7 is a right view thereof;

FIG. 8 is a left view thereof; and,

FIG. 9 is an enlarged sectional view thereof indicated in FIG. 6, but the controller body is not shown for ease of illustration.

The broken lines shown in the drawings depict portions of the controller for computer that form no part of the claimed design.

1 Claim, 9 Drawing Sheets
